ABSTRACT OF THE DISCLOSURE

A biocidal combination of 2,4,5-trichlorophenol and methylene bishiocyanate useful for the protection of leather and for other fields where biocidal treatment is desired.

This invention relates to antimicrobial compositions and more particularly to synergistic antifungal compositions containing 2,4,5-trichlorophenol and methylene bishiocyanate.

The control of microorganisms is a persisting problem. The variety of organisms and the varying conditions under which control is needed present particular problems which do not admit of easy solutions. Protection against microorganisms such as bacteria and fungi is necessary in many fields such as the textile, paper, leather, wood, coatings and food industries. Many types of preservatives have been employed in these and other such fields for protection against attack by microorganisms.

In the leather industry where the hides and skins of animals are processed into a variety of products, the animal origin of the leather product provides a favorable nutrient medium for the growth of microorganisms such as fungi and bacteria. At several stages in the preparation of leather from animal skins and hides, microbial attack is an important problem, and the use of biocides is required to prevent damage to the hides or leather. Hides, after removal from the animal carcass, are preserved prior to leather-making by salting, which is a process that dehydrates the hides. Properly salted hides are not readily attacked by microorganisms. However, prior to leather-making, the hides must be rehydrated by soaking, making them again susceptible to the growth of microorganisms. During the soaking period, biocides generally are added to inhibit microbial growth.

Following the liming (dehairing), bating, pickling and tanning steps in leather manufacture, the tanned hides generally are stored for variable periods of time under a variety of conditions. Tanned hides under storage conditions can be attacked by microorganisms, especially fungi. Thus, it is good practice to protect these tanned hides by application of an antifungal agent. Finished leather exposed to high humidity also is susceptible to fungal growth, whereby it is generally considered desirable to have a fungicide present on the finished leather.

Among the various compounds suggested for biocidal purposes, the halophenols have been widely used as preservatives and are known to have desirable antimicrobial properties. The halophenols also are frequently used in admixture with other compounds and materials in order to provide improved results. An example of such combinations is disclosed in U.S. Pat. 1,879,351, where halophenols, for example trichlorophenol, are used in conjunction with benzoic acid and substituted benzoic acids or derivatives thereof.

Various organic mercury or zinc compounds and organo-sulfur compounds also are known to have effective antimicrobial properties. Included in the latter group of compounds are the organic thiocyanates and in particu-

2

lar, for purposes of the present invention, methylene bishiocyanate. The antimicrobial properties of methylene bishiocyanate are disclosed in U.S. Pat. 3,252,855.

In selecting an appropriate biocide, properties such as toxicity, odor, color, and stability as well as specificity for particular organisms or broad range antimicrobial activity should be taken into consideration. For example, in the leather industry in conjunction with the use of the halophenols, it is common practice to extend the range of activity against microorganisms by combining a compound having primarily antibacterial activity (such as pentachlorophenol) with a second compound having primarily antifungal activity (such as trichlorophenol). It is known, however, that the antimicrobial agents presently in general use in the leather industry suffer from a variety of deficiencies, which include insufficient effectiveness, instability, toxicity, and incapacity to restrain resistance development.

In brief, the present invention, as distinguished from prior combinations for extending the antimicrobial range of activity, is concerned with the use of two compounds having substantially different chemical moieties, namely 2,4,5-trichlorophenol and methylene bishiocyanate, in a synergistic antifungal combination. It has been found according to the present invention that said compounds can be combined in admixture with each other to provide a substantial and significant mutual enhancement of antifungal activity.

A principal advantage of the present combination is that lower concentrations of each component are required to achieve the same antifungal effectiveness as a larger concentration of the individual components alone. Use of lower concentrations reduces toxicity as well as the cost of application. Another advantage in the practice of the present invention, particularly since the combination employs two substantially different chemical moieties, is that the improved antifungal activity will be complemented with a broader antimicrobial spectrum of activity and with hindrance to resistance development.

The 2,4,5-trichlorophenol component of the present invention can be readily prepared by treatment of 1,2,4,5-tetrachlorobenzene with methanolic NaOH in an autoclave at 160° C. for several hours. The methylene bishiocyanate component can be prepared by first reacting methylene chloride with sodium iodide and hydrochloric acid in acetone solvent and thereafter reacting the resulting product with sodium thiocyanate under conventional refluxing temperatures and conditions. Although these specific methods of preparation of the active antifungal components of the present invention are disclosed, it will be understood that the invention is not limited to any particular method of preparation of these components.

In carrying out the present invention, the ratio of the active components to each other can vary somewhat but it is preferred to combine about one part by weight of methylene bishiocyanate with from about 5 to about 20 parts by weight of 2,4,5-trichlorophenol.

In practice, the antifungal combination of 2,4,5-trichlorophenol and methylene bishiocyanate can be used in admixture with various diluents, solid and liquid carriers, surface active agents, and also with other antimicrobiologically effective additives.

In the case of solid carriers, materials having large surface areas such as bentonite, kieselguhr, fuller's earth, clay, pyrophyllite talc and the like can be employed as well as nonclay carriers such as lignocellulose and wood flour.

When it is desired to use the antifungal combination of the present invention in liquid form, it is desirable to dissolve or disperse the combination in a liquid carrier.

3

Water, alcohols, and various oils and organic solvents can be used. Suitable oils include those of animal, vegetable, mineral and synthetic origin such as soy bean oil, castor oil, cod liver oil, kerosene and the like.

Dispersion of the active antifungal components in a liquid carrier can be promoted by agitation in the presence of a surface active agent. Any of the well-known emulsifying or dispersing agents may be employed for this purpose, for example, sodium lauryl sulfate, aliphatic and aromatic sulfonates such as sulfonated castor oil or various alkaryl sulfonates such as the sodium salt of monosulfonated nonyl naphthalene. Non-ionic types of emulsifying agents can also be used such as the higher molecular weight alkyl polyglycol ethers. The amount of surface active agent in the liquid formulation will generally range from about 1% to about 20% by weight of the active antifungal components.

The range of concentration of the total active antifungal components in the liquid or solid formulations used in practice can vary somewhat and will depend, in part, on the particular end use to which the formulation is put. Concentrations as low as a fraction of 1% by weight of the active components may be used, for example, concentrations as low as about 0.1%. Very highly concentrated formulations, for example, those containing up to about 50% by weight of the active components may be diluted before use if desired. A formulation containing 20% 2,4,5-trichlorophenol and 2% methylene bishthiocyanate by weight is preferred.

The following examples will serve to illustrate the invention although the invention is not to be limited to these specific examples. All percentages are on a weight basis unless otherwise specified.

EXAMPLE 1

A liquid formulation of the antifungal combination of the present invention containing 20% 2,4,5-trichlorophenol and 2% methylene bishthiocyanate by weight is prepared as follows:

(A) To 2 grams of methylene bishthiocyanate ("Cytox" 3040) add 62 grams of cresylic acid and stir until solution is achieved. Add 15 grams of methanol and 20 grams of 2,4,5-trichlorophenol ("Dowicide" 2). Stir the blend until in solution and then add one gram of sodium-N-methyl-N-oleoyltaurate ("Igepon" T-33).

An alternative method of preparing the above formulation is to blend together the cresylic acid, alcohol and surface active agent and then add the active antimicrobial materials.

The above liquid formulation is an excellent antimicrobial composition which exhibits activity against a broad spectrum of fungi and bacteria. This formulation is useful for preservation in the leather, textile, paper, coatings, and other industries. In the above formulation, the ratio of the active materials to each other can vary from about one part of methylene bishthiocyanate to from about five parts to about twenty parts by weight of the 2,4,5-trichlorophenol with substantially equivalent antimicrobial results.

In the above example, other diluent materials, for example, kerosene, mineral spirits, linseed oil and naphthol can be substituted for the diluent cresylic acid with substantially equivalent results. Other alcohols, for example isopropanol, butanol and ethanol can be substituted for the methanol with substantially equivalent results and other emulsifying agents, for example, sodium-N-cyclohexyl-N-palmitoyltaurate and the oleic acid ester of sodium isethionate can be substituted for the sodium-N-methyl-N-oleoyltaurate with substantially equivalent results.

EXAMPLE 2

In order to demonstrate the synergistic antifungal activity of the 2,4,5-trichlorophenol and methylene bishthiocyanate combination, the antimicrobial formulation of Example 1(A) was compared with two other formula-

4

tions (B and C) which were identical to A in every respect except that B did not contain the methylene bishthiocyanate and C did not contain the 2,4,5-trichlorophenol. These formulations were tested at several dilutions for antifungal activity on petri dishes inoculated with a mixture of *Aspergillus oryzae* and *A. niger*, and incubated at 30° C. for 7 days. The results were as follows:

	Concentration required for growth inhibition (mcg./g.)
10 Formulation:	
A.....	5.88 TCP plus 0.59 MBT.
B.....	8.16 TCP.
C.....	2.00 MBT.

NOTE.—TCP=2,4,5-trichlorophenol; MBT=methylene bishthiocyanate

A mutual enhancement of antifungal activity by the combination of 2,4,5-trichlorophenol and methylene bishthiocyanate is evident from the above findings that substantially lower concentrations of each component are required than that needed for each compound alone for growth inhibition.

In a similar manner as above the synergistic combination of 2,4,5-trichlorophenol and methylene bishthiocyanate is effective against growth of other fungi of the genera *Aspergillus*, *Myrothecium* and *Penicillium*, and bacteria of the genera *Aerobacter*, *Bacillus* and *Pseudomonas*.

EXAMPLE 3

The effectiveness of the combination of 2,4,5-trichlorophenol and methylene bishthiocyanate as a leather preservative is demonstrated by the following test made on leather stock "in the blue" received immediately out of the tan drum.

Procedure

(1) Leather strips cut 1/2" x 6" (about 30 g./strip) were either (a) soaked in the test solution (equal weights of test solution and leather strips placed on reciprocating shaker for 30 minutes), or (b) dipped in the test solution (equal weights of test solution and leather strips in petri dish in which the leather strips were pulled slowly through the test solution).

(2) Tanner's Fungal Spore Culture on sand was sprinkled on both sides (grain and flesh) of the leather test strips.

(3) The inoculated leather test strips were incubated at 30° C. for up to 18 days in barrel jars containing water in the bottom of the jar.

Results

Using the formulation A of Example 1, in aqueous solution at various concentrations as one test solution and using an aqueous solution of "Sterozol" N (a commercially-available antimicrobial formulation which does not contain any methylene bishthiocyanate but contains 15% 2,4,5-trichlorophenol, 5% pentachlorophenol and 20% o-phenylphenol) in similar concentrations as the other test solution, the antifungal test results are recorded in the following table:

Formulation	Concen- tration, percent	Growth (days)							
		6	8	11	15	18	6	8	
Sterozol N.....	0.025	—	±	+	+	+	—	—	
	0.0125	+	±	+	+	+	—	—	
	0.00625	+	—	—	—	—	+	—	
	0.0031	+	—	—	—	—	+	—	
Formulation A, 20% TCP 2% MBT.....	0.025	—	—	—	—	+	—	+	
	0.0125	—	—	+	+	—	—	+	
	0.00625	+	—	—	—	—	+	—	
	0.0031	+	—	—	—	—	+	—	

NOTE.——=no growth; + =growth.

The above test results show that the formulation A containing the combination of 2,4,5-trichlorophenol and methylene bishthiocyanate inhibits fungi at a significantly

lower concentration than does the "Sterozol" N formulation used for purposes of comparison and that the formulation A combination is about two times better than an equivalent amount of "Sterozol" N.

Various modifications and adaptations of the herein-defined invention can be made, after reading the foregoing specification and claims appended hereto, by the person skilled in the art without departing from the spirit and scope of the invention. All such modifications and adaptations are included within the scope of the invention as defined in the appended claims.

What is claimed is:

1. An antifungal composition comprising from about 5 to about 20 parts by weight of 2,4,5-trichlorophenol and about one part by weight of methylene bis thiocyanate. 15

2. The antifungal composition of claim 1 wherein the 2,4,5-trichlorophenol is present in an amount of about 10 parts by weight of the methylene bis thiocyanate.

3. The method of inhibiting the growth of fungi comprising applying to a substance which is subject to attack by fungi a fungus inhibiting amount of the composition of claim 1. 20

4. The method of inhibiting the growth of fungi comprising applying to a substance which is subject to attack by fungi a fungus inhibiting amount of the composition of claim 2. 25

5. An antifungal composition comprising from about 0.1% to about 50% by weight of a mixture of the composition of claim 1 and from about 99.1% to about 50% by weight of antifungally inactive components selected from the group consisting of bentonite, kieselguhr, fuller's earth, clay, pyrophyllite talc, lignocellulose, wood flour, water, methanol, ethanol, isopropanol, butanol, soybean oil, castor oil, cod liver oil, linseed oil, kerosene, cresylic acid, mineral spirits, naphthol, sodium lauryl sulfate, sul-

fonated castor oil, sodium salt of monosulfonated nonyl naphthalene, sodium-N-methyl-N-oleoyl-taurate, sodium-N-cyclohexyl-N-palmitoyltaurate and oleic acid ester of sodium isethionate.

5 6. The method of inhibiting the growth of fungi comprising applying to a substance which is subject to attack by fungi a fungus inhibiting amount of the composition of claim 5.

10 7. The method of inhibiting the growth of fungi on animal hides and leather comprising applying to the animal hide or leather a fungi inhibiting amount of the composition of claim 1.

15 8. The method of inhibiting the growth of fungi on animal hides and leather comprising applying to the animal hide or leather a fungi inhibiting amount of the composition of claim 2.

20 9. The method of inhibiting the growth of fungi on animal hides and leather comprising applying to the animal hide or leather a fungi inhibiting amount of the composition of claim 5.
